CARTON

William P. Frankenstein, Cincinnati, Ohio

Application November 17, 1939, Serial No. 305,004

3 Claims. (Cl. 229—34)

This invention relates to improvements in a carton formed from a single piece or blank of card or fibre board material of the class which is shipped to the user in a knocked down condition and is set up by merely actuating the sides or walls to a position normal to the bottom.

In the past, numerous attempts have been made to provide such a box or carton, but, due to their construction, the sides were insufficiently rigid to remain in their upright or normal position while being filled with the merchandise to be subsequently shipped or displayed therein, without the operator or filler holding the said sides or walls in their necessary position while filling the same. In other attempts to produce a carton of the inexpensive variety, the construction was such that in setting up the carton, the same was damaged and a shoddy looking article resulted.

It is therefore one of the principal objects of the present invention to provide a relatively inexpensive carton adapted to be shipped to the user in a knocked down condition and in which, when the walls are set up, they remain in a vertical position with no sagging of the said walls, whereby the operator or filler may very readily and rapidly place the contents therewithin.

Another object of this invention is the provision of a carton as above referred to, in which the corners of the carton walls are permanently secured to one another with certain walls having one or more folds therein, caused by knocking down the carton, and in which these walls are rigidly reinforced when in upright position normal to the bottom of the carton.

A further object of this invention is the provision of a one piece carton adapted to be shipped in a knocked down condition, and in which the folded walls, when raised from its knocked down position, is locked in the raised position, thereby locking all four walls in position against inward bending or sagging.

A still further object of this invention is the provision of a four sided carton formed of a single blank of card or fibre board material, adapted to be shipped to the user in a knocked down condition, in which certain of the walls are provided with folds to effect the knock down of the carton, and in which means are provided for permanently straightening the said folded walls of the carton.

A still further object of the invention is the provision of an inexpensive carton and integral cover formed from a single blank of card or fibre

board material adapted to be shipped to the user in a knocked down condition, and in which the walls, when erected to their normal position, are held against inward or outward sagging, whereby the carton may be readily filled and its cover readily arranged in position relative thereto.

Other objects and advantages of the present invention should be readily apparent by the reference to the following specification, considered in conjunction with the accompanying drawings forming a part thereof, and it is to be understood that any modifications may be made in the exact structural details there shown and described, within the scope of the appended claims, without departing from or exceeding the spirit of the invention.

In the drawings:

Fig. 1 is a perspective view of a carton or box embodying the improvements of this invention and illustrated in a set up position.

Fig. 2 is a perspective view of the box or carton of Fig. 1 when in a knocked down or shipping condition.

Fig. 3 is a fragmentary, perspective view showing the box in the process of erection and at a point between the knocked down position of Fig. 2 and the fully erected position of Fig. 1.

Fig. 4 is a fragmentary, horizontal, sectional view through one end of the box, taken on line 30 4—4 of Fig. 1.

Figs. 5 and 6 are respectively fragmentary, sectional views taken through the walls at right angles to one another, on lines 5—5 and 6—6 on Fig. 4.

Fig. 7 is a plan view of the blank from which the carton of Fig. 1 is made, this blank showing the first steps in the process of manufacture after it has been blanked out.

Fig. 8 is a view similar to Fig. 7, showing the next two steps in the manufacture of the carton, the steps being respectively shown at the left and right hand ends thereof.

Fig. 9 again being a view similar to Figs. 7 and 8, and showing the next three steps in the manufacture of the carton of Fig. 1, one step being shown at the left hand end and the next two steps at the right hand end thereof.

Fig. 10 is a transverse, sectional view through the carton when in the knocked down condition, and the view is taken on line 10—10 on Fig. 2.

Fig. 11 is a view of a blank which forms a carton considerably longer than wide, instead of having a substantially rectangular bottom as in the carton of Fig. 7, and further showing the

operating structure of the carton at the carton walls or sides opposite from that shown in Fig. 7.

Fig. 12 is a perspective view of the blank of Fig. 11 in the completed condition and knocked down.

Fig. 13 is a perspective view, with a small corner broken away, of the erected carton formed from the blank of Fig. 11.

Fig. 14 is a fragmentary, perspective view of a corner of a carton formed from a modified blank.

Fig. 15 is a plan view of the corner of a modified blank from which the corner of Fig. 14 is formed.

Fig. 16 is a perspective view showing the blank of Fig. 15 in a knocked down condition.

Fig. 17 is a fragmentary, vertical, sectional view through one of the walls of Fig. 14, taken on line 17-17 on said Fig. 14.

Fig. 18 is a fragmentary, longitudinal view through the knocked down view of Fig. 16, taken on line 18-18 on said Fig. 16.

Fig. 19 is a plan view illustrating in part the blank and in part the blank in folded, knocked down position, and which blank is modified to provide a combined carton and cover integral with one another, the blank being a modification of that shown in Fig. 11.

Fig. 20 is a perspective view showing the carton of Fig. 9 in erected position and the cover in knocked down position.

Fig. 21 is a perspective view, partly in section, showing the carton and cover of Figs. 19 and 20 in erected and closed position.

Figs. 22 and 23 are respectively plan and perspective views similar to Figs. 19 and 20, utilizing the blank of Fig. 7 for forming a carton and integral cover.

Fig. 24 is a perspective view of a box or carton with an integral cover made from a blank similar to that of Fig. 7 modified to include the cover.

Throughout the several views of the drawings, similar reference characters are employed to denote the same or similar parts.

As was noted above, this invention pertains to a box or carton formed of paper or fibre board material and may be described as of the more or less inexpensive type of such box or carton and is shipped to the user in a knocked down condition, requiring the user merely to lift two of the opposed walls and thereby fully erect the box or carton for use. It should be noted that throughout the specification, reference will be made to side walls and end walls for the box or carton, but these terms are merely for clearness in description and are relative terms, as any wall or walls designated as end walls, may, under other circumstances, be designated as side walls.

Specifically referring to the drawings, Fig. 1 shows the box or carton in its erected position and comprises a bottom 25 having upstanding therefrom the opposed end walls 26 and 27 and side walls 28 and 29. The box or carton of Fig. 1 was erected from the knocked down position of Fig. 2, where the carton is shown with the end walls 26 and 27 as folded down on to the upper surface of the bottom 25, with the side walls likewise folded down and parallel with the bottom, but with the ends thereof resting on top of the end walls.

This carton or box was formed from the blank of Fig. 7, which shows the bottom panel 25 de-

fined by dotted lines 30, 31, 32 and 33 which are the fold lines on which the end walls 26, 27, 28 and 29 are respectively upwardly bent. The end wall 26 is formed of a pair of panels 34 and 35, respectively defined by the left hand end of the blank and the solid and dotted lines 36 and 27 which are respectively cut and fold lines between the panels 34 and 35, and these cut and score lines 36 and 37 define one end of the end panel 35 whose inner end is defined by the fold line 30. The panel 34 in the erected carton forms the inner section of the end wall, while the panel 35 forms the outer section thereof and in addition the panel 34 forms the means, as will later be described in detail, for maintaining the box or carton in its final or erected position.

The lateral ends of the panel 35 are defined by dotted lines 38 and 39 which form a hinge connection for attaching tabs 40 and 41, and which tabs are employed for securing the side walls to the end walls. Hingedly connected with the attaching tabs 40 and 41 are the locking tabs 42 and 43, respectively connected with the tabs 40 and 41 at the hinge or fold lines 44 and 45. The inner ends of the cut lines 36, between the end wall sections 34 and 35, are connected with the adjacent corners of the bottom panel 25 by diagonal score or fold lines indicated in the drawings by dotted lines 46 and 47 and, as will later be made clear, constitute the hinge connection between the walls or sides of the box and carton whereby they may be folded to the knocked down position of Fig. 2.

The opposite end wall 27 is identical in all respects with that just described, and it is believed unnecessary to redescribe the component parts thereof, and they are indicated in the drawings by the same reference characters as above employed.

The side walls 28 and 29 are merely panels of substantially the length of the box or carton bottom and a width equal to the height of the box. It should be noted, however, that the lengths of these sides may be enough shorter than the attached portion of the bottom panel to take care of the thickness of the blank when in erected position, since, with the blank as just described and as erected in Fig. 1, these side walls are within the end walls. Similar clearances are provided at the ends of the inner end wall sections 34, as well as at the ends of the attaching flaps 40 and 41 and locking flaps 42 and 43 so that the parts are properly fit to produce a neat construction.

With the blank die cut as illustrated in Fig. 7 and above described, it is passed through a gluing and folding machine, the various steps being illustrated in Figs. 7, 8 and 9, each figure illustrating one or more operations in the complete manufacture of the box or carton. The first step is illustrated in Fig. 7, which consists of applying glue or adhesive to the attaching lugs 40 and 41 as well as applying glue or adhesive to the inner surface of the outer end wall section 35; these glue or adhesive spots being indicated by the reference characters 48 and 49 on the attaching tabs 40 and 41 and 50 on the inner end wall panel 35. It will be appreciated that in each of the manufacturing steps to be described, similar steps are effected at each end of the blank, and it will be readily understood that instead of applying the glue or adhesive to the tabs 40 and 41 and outer wall panel 35, the said glue may be

applied to the locking tabs 42 and 43 and wall panel 34.

With the glue on the tabs as above described, the locking tabs 42 and 43 are folded along their score lines 44 and 45, on to the attaching tabs 40 and 41, and the end wall panel 34 is folded along the fold line 37 on to the panel 35 and sufficient pressure placed thereon to insure these parts securely adhering to one another. This folding step in the process of manufacture is illustrated in the left hand end of Fig. 8. The next step consists of folding all of the parts just referred to along the score or fold line 30, thereby bringing the inner surface of the inner end wall panel against the bottom panel 25, and at the same time bringing the locking tabs 42 and 43 against the inner surface of the side walls 28 and 29, as illustrated in the right hand end of Fig. 8. The next step in the manufacture of the carton or box consists of holding the end walls in the position of the right hand end of Fig. 8 and folding the locking tabs, attaching tabs and the portions of the outer end wall panel beyond the diagonal fold lines 46 and 47 along these fold lines 46 and 47 to the positions illustrated in the left hand end of Fig. 9. In other words, this step of the process places the outer surface of the end wall panels on itself with the attaching and locking tabs extending temporarily beyond the bottom blank. This step is followed by the step of folding the locking and attaching tabs back into parallel relations with the bottom of the panel and folding same along the score or fold lines 38 and 39 to the positions illustrated in the right hand end of Fig. 9. At this time, glue or adhesive, indicated by the reference characters 51 and 52, is applied to the opposite ends of the side walls, and these side walls then folded down on to the end walls to the position illustrated in Fig. 2 and suitable pressure applied to assure the adhesion of these parts. It will be appreciated that the glue or adhesive spots 51 and 52 may, instead of being applied to the end walls 28 and 29, be applied to the outer surface of the attaching tabs, or the exposed surface thereof, as seen in Fig. 9.

From the foregoing, it will now be appreciated that the knocked down position of the box or carton is made in one continuous process through a machine, and that it is ready for assembly by merely lifting the said end walls 26 and 27. The process of erecting the carton from the knocked down to the erected position is illustrated near the completion thereof in Fig. 3, which shows the inner end wall panel 34 as arched, while passing between the locking tabs or lugs 42 and 43 to the erected and secured position. As will be seen from Fig. 3, the inner edge 53 of the locking tab or lug 43 is spaced from the outer wall panel 35 a distance which is substantially equal to the thickness of the board from which the carton is made, thereby providing a notch 54 into which the ends of the inner wall section 34 snap in the finally erected position, as illustrated in Figs. 1 and 4.

Figs. 4, 5 and 6 show the positions of the different components of the carton blank when in erected position, showing the end wall as of double thickness, as in Figs. 4 and 5, with the end wall sections integral and folded at their centers. It will be appreciated, however, that the inner end wall panel 34 may be separate from the outer panel and held in position by the glue or adhesive 50 and still function as a set up member. In Figs. 4 and 6, the attachment

of the side and end walls to one another and the relation of the attachment and locking tabs to one another and to the rest of the structure is clearly illustrated, with the locking and attaching tabs as integral and folded on one another. In this connection, it will also be readily appreciated that the locking tab or tabs may be separate pieces glued or otherwise secured in position with respect to the side and end walls.

It will readily be seen that the inner wall section 34, since it is unscored and therefore unbent, will hold erect the scored and normally bent outer end wall panel and will prevent this wall from tending to assume the position into which it was bent in its manufacture and prior to its shipment. By this construction, a very grave fault of here-to-fore cartons of a similar nature is positively and definitely overcome. At the same time, the said inner end wall panel 34 locks the side walls 28 and 29 in their erected position, since a relatively close and snug fit is had between this panel and the said side walls, thereby each reacting against the tendency of the other to sag or fold to the position into which it was placed during the manufacture. In Figs. 11, 12 and 13, a box or carton of a substantially similar construction is illustrated, except that the shorter or end walls are formed of a single thickness of material, while the longer or normally accepted side walls are provided with the material for folding down the walls. As shown in Fig. 13, the box or carton comprises a bottom 55, upstanding from which are the opposed end walls 56 and 57 and the opposed side walls 58 and 59, which are set up by the user from the knocked down position illustrated in Fig. 12.

The blank from which the carton of Fig. 13 is made is illustrated in Fig. 11 and has the bottom panel 55 defined by the fold or score lines indicated by dotted lines 60, 61, 62 and 63, and which score lines respectively, hingedly connect with the bottom panel, the end walls 56 and 57 and the outer wall sections or panels 64 of the side walls 58 and 59. In this modification, the so-called end walls 56 and 57 are of single thickness, as were the said walls 28 and 29 of the carton or box in Fig. 1, while the so-called side walls 58 and 59 are of substantially double thickness and are formed with the same configuration and construction as were the end walls 26 and 27 above.

Accordingly, the side wall 58 includes the outer wall section or panel 64 to which is hingedly connected, along the dotted score line 65, the inner wall panel section 66, which also constitutes the means for holding the walls in their desired erected position. The opposite ends of the side wall panels 64 and 65 are free of one another as by the cut line 67 which is of a length substantially equal to the height of the said outer side wall panel section 64. Secured to the ends of the outer side wall section 64, as by dotted score lines 68 and 69, are the attaching flaps 70 and 71. The attaching flaps 70 and 71 in turn have connected to them, by way of dotted score lines 72 and 73, the locking flaps 74 and 75. The adjacent corners of the bottom panel 55 are connected with the inner ends of the cut lines 67 by dotted score lines 76 and 77.

From the foregoing, it will be appreciated that the blank of Fig. 11 has the same construction as that of Fig. 7, except that the connecting and locking mechanism is carried by the so-called side walls of the carton or box instead of by the end walls. The blank of Fig. 11 passes through

the same manufacturing steps as that above described, and in each case two opposed walls of the box or carton are folded down against the upper surface of the bottom panel, and the other remaining opposed walls are folded down parallel with the bottom, lying on the adjacent ends of the first pair of opposed walls. In order to erect the carton or box from its knocked down or folded position to its usable position, it is merely necessary to swing upwardly the uppermost walls, which, through their hinge connection with the other walls, causes same to assume their erect position, and the co-operating locking means are snapped to position to hold the walls in their vertical erected position. In this connection, it should be noted that the locking tabs 74 and 75, when in their finally assembled position, are carried by the end walls 56 and 57, and spaced from the outer side wall panel sections 64 a distance sufficient to permit the inner side wall panel section to snap therebehind.

In connection with the box or carton of Figs. 11, 12 and 13, it should be noted that there is illustrated the minimum lateral dimension to which the box or carton may be conveniently made. In other words, the width or distance between the dotted fold lines 62 and 63 is just twice the height of the upstanding side walls, and with this type of construction the attaching flaps 70 and 71 from each side wall would abut one another, thereby in effect producing a knocked down wall box or carton which in its final erected position has double walls throughout. In this connection, it will be readily appreciated that any size box or carton may be made with double thickness end walls by merely making the attaching flaps of a sufficient length.

In Figs. 14 to 18 inclusive, there is illustrated one corner of a modified construction, the modification consisting in the elimination of the locking flaps, such as 42 from Fig. 7 or 75 from Fig. 11, the blank otherwise being identical with that described. With this modified construction, the glue spots 48 are eliminated from the attaching flap 40 and in its stead, when the blank reaches the stage in its manufacture exemplified by the left hand end of Fig. 9, the ends of both the inner and outer wall section panels 34 and 35 have each, adjacent the cut line 36, applied thereto spots of cement or adhesive 78 and 79. This type of cement or adhesive is such, which, when first applied, will adhere to the surface; but, when dry, will not adhere to a second surface, regardless of the amount of pressure that is placed thereon, but which cement or adhesive, when brought into contact with the dry surface of a second spot of similar cement or adhesive, adheres to such an extent as to defy separation.

As will be seen in Fig. 18, these spots of cement or adhesive 78 and 79 are out of contact with one another when the carton is in a knocked down position. When erected, however, the spots 78 and 79 are brought into direct contact, as shown in Fig. 17, and by pressing these spots to one another through pressure of the fingers applied to the inner and outer wall sections 34 and 35, they bond the said wall section panels to one another, and thereby lock the walls in an erected position, since the inner wall panel section 34 has a length to snugly engage the inner surfaces of the attaching flaps 40 and 41 as above described.

From this it will be seen that a blank and subsequent erected box or carton, as illustrated in Figs. 14 to 18 inclusive, has the same advantages and erecting simplicity as the one previously de-

scribed, without the use of the locking tabs or lugs 42 and 43 or 74 and 75.

In Figs. 19, 20 and 21, there is illustrated a box or carton embodying the improvements of this invention, including an integral cover or lid for the box or carton. The example shown in these figures is based on the blank of Fig. 11; in other words, a blank with the connecting cover means located at the side, which carton carries the wall hinging and locking means. Specifically referring to Fig. 19, the blank there shown is provided substantially centrally of its length with a panel 80 located between score lines indicated in the drawings by dotted lines 81 and 82. The width of the panel is substantially identical with the height of the upstanding walls, as this panel forms the back for the box or carton. The inner side wall panel 66 is cut away, as between the cut lines 83 and 84, while the outer side wall panel 64 is cut away to provide a triangular shaped gusset 85, hingedly connected by the score line 86 with the adjacent portion of the outer panel section 64, and hingedly connected by the score line 87 to the adjacent portion of the back panel 80. The gusset 85 is further provided with a score line 88 extending normal to the free edge of the gusset and intersecting the score lines 86 and 87.

The blank of Fig. 19 is put through the same manufacturing steps as the blanks of Figs. 11 and 7, and at one point in this process, a spot of glue 89 is applied to the back panel 80 adjacent the score line 87, or this glue may be applied to the gusset 85 between the score lines 87 and 88, so that when the side walls are folded down on to the bottom panel, the portion of the gusset between said last named score lines 87 and 88, is permanently and definitely secured to the back panel 80. In the manufacture of the box or carton with the cover integral therewith, and shown in Figs. 20 and 21, the finally folded blank takes the form illustrated in the lower half of Fig. 19 and is in this condition when shipped to the customer, or with the parts as shown in the lower half of Fig. 19, that portion of the folded blank to the right of score line 81 may be folded on to the top of the other portion.

When it is desired to set up this box or carton, one or the other of the end walls is raised. As shown in Fig. 20, for example, the left hand end wall was raised to its final position, allowing the portion of the inner side wall panels adjacent thereto to snap into position and thereby partially raising the back panel 80 since the gusset connection 85 between the side walls and back panel will effect this position of the back wall with the folded or knocked down cover assuming the position shown in Fig. 20; that is, inclined downwardly. After the box or carton has been filled with the desired merchandise, the remaining or right hand wall, front of the cover, is raised to snap the inner side wall sections adjacent thereto into position, and the cover then placed over the box or carton, as illustrated in Fig. 21.

It will be appreciated that, instead of setting up the blank as just described, the right hand end thereof may be employed as the box or carton and the left hand end as the cover and setting up in this manner, as illustrated in Fig. 23.

In Figs. 22 and 23, a combined box or carton and its integral cover is illustrated, utilizing for this purpose the basic blank shown in Fig. 7; that is, with the end walls carrying the walls hinge connection and the locking device, and

with the side walls having the gusset formed therein. As shown in Fig. 22, substantially centrally of the blank, there is a panel 90 between the fold lines 91 and 92, which lines are spaced a distance equal to the height of the side walls of the carton or box. The side wall between the fold lines 91 and 92 is cut away to provide a substantially triangular shaped gusset 93 hingedly connected by the fold lines 94 and 95 respectively to the adjacent ends of side wall 28 and back panel 90, and the gusset has a diagonal dotted or fold line 96. Again the back panel 90 is illustrated as having applied thereto, adjacent the fold line 95, a spot of glue 97, whereby the portion of the gusset 93 between the fold lines 95 and 96 is secured to the back panel 90. This blank, in the knocked down or folded position, is as illustrated in the lower half of Fig. 22, and in order to erect the said walls, the side walls 28 and 29 of the bottom portion, illustrated in Fig. 23, the left hand portion of the blank, is raised to snap the front into position and hold the said side walls erect with the remaining or cover portion lying flat, parallel with the box or carton. As was noted above, either the portion to the right of the score line 92 or the portion to the left of the score line 91 may be used as the bottom and other as the top, depending upon which way the blank is laid down and usually printed.

It should be noted that a similar connecting arrangement between a box or carton and its integral cover is illustrated in U. S. Patent No. 1,993,323, issued on March 5, 1935, to Wm. P. Frankenstein.

It will be appreciated that the panel forming the top for the carton will be slightly larger than the panel forming the bottom, in order to take care of the thickness of the depending walls from the top and so that they may be disposed around the walls of the bottom. It should also be noted that the walls of the top need not be as high as the walls for the bottom, as the top wall or flanges need not extend to the bottom of the box or carton walls, but since the material cut out to shorten the top walls or flanges would be waste material anyway, they have been shown as made the full height of the box or carton walls.

In Fig. 24, there is illustrated a box or carton made from a blank similar to the blank in Fig. 7, which sets up to the box or carton of Fig. 1, but with a top or cover integral with one of the side walls. In other words, the box or carton of Fig. 24 is made from a blank substantially identical with that in Fig. 7, but with a panel portion integral with the top edge of one of the side walls 28 and 29.

Specifically, and referring to Fig. 24, the end wall 28 has its top portion represented by a dotted or hinge line 98 hingedly connecting thereto the top panel 99. Hingedly connected to the three remaining sides of the top panel 99 are tabs 100, 101 and 102 which form flanges for the top to embrace the box or carton walls. It will, of course, be understood that the area of the top panel 99 is sufficiently greater than the area of the bottom panel 25 to permit the top flanges 100, 101 and 102 to embrace the carton walls.

From the foregoing, it will be noted that there has been provided a box or carton which is relatively inexpensive to manufacture, and in fact would produce what is known in the trade as a "cheaper box," although it may be employed for the most expensive type of container or shipping carton, and in which the box or carton is shipped

in a knocked down, compact condition, requiring the user to merely lift the two uppermost exposed walls and readily snap same in position and be locked therein, or the said walls may be permanently secured in position by a light pressure between the fingers, when the snap lock is not employed, but the "Latex" type of cement of Fig. 15 is employed. It will further be noted that the wall provided with the necessary bends, in order to fold the same inwardly, is positively reinforced by a member at no time weakened by score or fold lines, and that this stiff member definitely, outwardly places the remaining walls, which, while without score lines, is being positioned out of its original folded and pressed position.

What is claimed is:

1. A box or carton comprising a bottom, up-standing walls from the sides of the bottom, two of said opposed walls having at opposite ends thereof connecting flaps for respective permanent attachment to the adjacent walls on the inner or opposed surfaces thereof, said connecting flaps having their lower edges spaced above the bottom, whereby the space between the opposed surfaces of the attached connecting flaps is less than the space between the opposed surfaces of the walls to which they are attached, said first mentioned opposed walls each having diagonal creases converging upwardly from the bottom and entirely traversing said walls, whereby the walls may be folded onto themselves and onto the bottom, a nonfoldable member carried by the upper edge of each of the foldable opposed walls and of a length substantially equal to the distance between the inner surfaces of said second mentioned pair of opposed walls, each of said nonfoldable members being secured in face contact to the inner surface of its respective foldable wall between the diagonal creases only thereof when the walls are in folded position, whereby upon erection of the walls the nonfolded member is forced within the space between the attaching flaps for holding the walls against sagging when erected, and locking flaps secured to the exposed surface of the attaching flaps and having a free edge adjacent said opposed walls behind which the nonfolded member is inserted and held against displacement except by force.

2. A box or carton comprising a bottom, up-standing walls from the sides of the bottom, two of said opposed walls having at opposite ends thereof connecting flaps for respective permanent attachment to the adjacent walls on the inner or opposed surfaces thereof, said connecting flaps having their lower edges spaced above the bottom, whereby the space between the opposed surfaces of the attached connecting flaps is less than the space between the opposed surfaces of the walls to which they are attached, said first mentioned opposed walls each having diagonal creases converging upwardly from the bottom and entirely traversing said wall whereby the walls may be folded onto themselves and onto the bottom, a nonfoldable member integral with and hingedly connected to the upper edge of each of the foldable walls between the diagonal creases only and free of said foldable walls outwardly from each of said creases, and said nonfoldable members being of a length substantially equal to the distance between the inner surfaces of said second mentioned pair of opposed walls, each of said nonfoldable members being secured in face contact to the inner surface of its respective foldable wall between the diagonal creases only thereof, when the walls are in folded position, whereby

upon erection of the walls the nonfolded member is forced within the space between the attaching flaps for holding the walls against sagging when erected.

3. A box or carton comprising a bottom, up-standing walls from the sides of the bottom, two of said opposed walls having at opposite ends thereof connecting flaps for respective permanent attachment to the adjacent walls on the inner or opposed surfaces thereof, said connecting flaps having their lower edges spaced above the bottom, whereby the space between the opposed surfaces of the attached connecting flaps is less than the space between the opposed surfaces of the walls to which they are attached, said first mentioned opposed walls each having diagonal creases converging upwardly from the bottom and entirely traversing said wall whereby the walls may be folded onto themselves and onto the

bottom, a nonfoldable member integral with and hingedly connected to the upper edge of each of the foldable walls between the diagonal creases only and free of said foldable walls outwardly from each of said creases and said nonfoldable member being of a length substantially equal to the distance between the inner surfaces of said second mentioned pair of opposed walls, each of said nonfolded members being secured in face contact to the inner surface of its respective foldable wall between the diagonal creases only thereof, when the walls are in folded position, whereby upon erection of the walls the nonfolded member is forced within the space between the attaching flaps for holding the walls against sagging when erected, and means for holding the nonfolded member against displacement except by force.

WILLIAM P. FRANKENSTEIN.
